DRAFT GEAR

Filed July 26, 1924

Inventor:
Herman C. Priebe

By G. A. Gray Atty

UNITED STATES PATENT OFFICE.

HERMAN C. PRIEBE, OF BLUE ISLAND, ILLINOIS.

DRAFT GEAR.

Application filed July 26, 1924. Serial No. 728,362.

My invention relates to railroad car draft gears and particularly to stop lugs employed in conjunction therewith, the invention residing in employing these lugs as a means 5 for assembling the car body and truck bolsters, or more specifically, the center or draft sills and truck bolsters.

An object of my invention, on the one hand, is to form the lugs separate from one 10 another as proposed in my prior Patent 1,525,885 so that each lug may be riveted to its related sill by power machinery before the lugs are secured together, thereby to assure a most effective, strong and durable 15 union between the lugs and the sills, and to eliminate weaknesses such as invariably occur as a result of manually riveting the lugs to the sills as is necessary by present known methods and means when the lugs are formed 20 integral with one another, and, on the other hand, to provide formations in or on the lugs cooperating with one another when the lugs are assembled together to provide a sleeve 25 for the reception of a king pin such as is usually employed in draft gears of this type for assembling the gear proper with a truck.

In carrying out my invention, the opposite stop lugs of a set upon the center or 30 draft sills of a car are merged or assembled into a unitary structure whereby each stop lug of such a structure supplements and strengthens the other and cooperates therewith in receiving strains and transmitting the same to the draft sills, such a unitary 35 structure being also shaped to constitute a sleeve or socket for the bolster assembling king pin.

In the preferred embodiment of the invention each of a pair of opposite stop lugs 40 has an upright transverse wing overlapping the upright transverse wing of the other, each overlapping part of the wing being formed with an upright semicylindrical recess matching the recess in the other to form 45 a cylindrical sleeve to receive a king pin.

The invention will be more fully explained by reference to the accompanying drawing in which Fig. 1 is a sectional plan view of a structure made in accordance with the preferred embodiment of the invention; Fig. 2 is a sectional view on line 2-2 of Fig. 1; and Fig. 3 is a sectional view on line 3-3 of Fig. 1.

The center or draft sills 1 and 2 are assembled in any suitable way with the body of

the car. The draft gear that is interposed between these sills at each end of a car includes an inner follower 3 and a yoke 4.

Elongated motion limiting lugs or cheek plates 5, 6 are riveted to the inner upright 60 sides of the center sills at each end of the car and are engaged by the inner end of said follower 3 to limit the inward motion of the followers. The lug 5 has an inwardly projecting upright wing 7 and the lug 6 65 has an inwardly projecting upright wing 8, these wings overlapping each other. The overlapping ends of the wings are secured together by rivets or bolts 9 which unite the wings into a unitary structure with the lugs, 70 the lugs and their united wings spanning the space between the draft sills. The wings are formed with symmetrically related matched semicylindrical recesses 10, 11 forming a sleeve or socket to receive a king pin 75 12 that serves to pivotally connect the center sills and body bolster structure with the underlying truck bolster.

As illustrated, the center sill structure and the lugs uniting the center sills are also parts 80 of the body bolster which is completed by the addition of wings 13 secured to and projecting laterally and outwardly from the center sills. The truck bolster 14 underlies the body bolster, these two bolsters being respectively 85 provided with the complemental members 15, 16 of a center bearing. The king pin 12 passes through the socket 10, 11 afforded by the united stop lugs and also through upright cylindrical or circular holes in the 90 center bearing members and the truck bolster. The resulting structure is compact and of great strength with a minimum of parts.

Changes may be made without departing 95 from my invention.

Having thus described my invention, I claim:

1. The combination with the draft sills of a car; of a truck bolster beneath said sills; a center bearing interposed between 100 the sills and truck bolster; a draft gear assembled with the draft sills; oppositely arranged stop lugs secured to the sills for limiting movement of the draft gear, each lug having a wing projecting toward 105 the other, these wings being bolted or riveted together and shaped to furnish an upright sleeve aligned with the center bearing; and a king pin passing through said sleeve and assembling the same and said 110

- sills with the center bearing and truck bolster.
2. The combination with the draft sills of a car; of a truck bolster beneath said sills; a center bearing interposed between the sills and truck bolster; a draft gear assembled with the center sills; oppositely arranged stop lugs secured to the sills for limiting movement of the draft gear
- 10 each having a wing projecting toward the other, these wings being bolted or riveted together to form a unitary structure, this structure being shaped to furnish an upright sleeve aligned with the center bearings; and a king pin passing through said sleeve and assembling the same and said sills with the center bearing and truck bolster.
- 15 3. The combination with the draft sills of a car; of a truck bolster beneath said sills; a center bearing interposed between the sills and truck bolster; a draft gear assembled with the draft sills; oppositely arranged stop lugs secured to the sills for
- 20 limiting movement of the draft gear, each lug having a wing projecting toward the other, these wings being bolted or riveted together, each wing being formed with an upright semicylindrical recess symmetrical
- 25 to and matching the semicylindrical recess of the other to furnish an upright sleeve aligned with the center bearing; and a king pin passing through said sleeve and assembling the same and said sills with the center bearing and truck bolster.
- 30 4. The combination with the draft sills of a car; of stop lugs carried by said sills, respectively, said lugs being formed separate from one another whereby they may
- 35 effectively be secured individually to said sills and thereafter secured together to provide a unitary structure, and cooperating
- formations on said lugs for the reception of a king pin.
5. The combination with the draft sills of a car, of stop lugs carried by said sills, respectively, said lugs being formed separate from one another whereby they may effectively be secured individually to said sills and thereafter secured together to provide a unitary structure, portions of said lugs overlapping one another, and a king pin engageable with companion formations provided in said overlapping portions to receive it.
- 55 6. The combination with the draft sills of a car; of a stop lug secured to each sill; each lug having a portion thereof overlapping a portion of the other lug, said overlapping portions being rigidly secured together to provide a unitary structure and having cooperating formations, respectively, providing a sleeve for the reception of a king pin.
- 60 7. As an article of manufacture, a stop lug for use in car draft gears, comprising a member of less width than the distance between a pair of draft sills to one of which it is adapted to be secured and having a vertically disposed king pin receiving formation adapted to mate with a similar king pin receiving formation in a companion lug.
- 65 8. As an article of manufacture, a stop lug for use in car draft gears, comprising a member of less width than the distance between a pair of draft sills and being adapted to be secured lengthwise to one of the latter, and having a king pin receiving formation extending at right angles to the lengthwise direction of the lug.
- 70 In witness whereof, I hereunto subscribe my name.
